WORM DRIVE ROAD ROLLER

Frank S. Davis, Flossmoor, and Hugh D. Woodier, Harvey, Ill., assignors to Austin Manufacturing Co., Harvey, Ill., a corporation of Illinois

Application November 7, 1928. Serial No. 317,847

6 Claims. (Cl. 74—57)

This invention relates to road rollers and more particularly to the provision of a novel construction of road roller provided with a worm drive.

Among the objects of our invention are to provide a road roller of stream-line design, which affords the operator an unobstructed view of the work of both front and rear rolls; further to provide a construction which entirely encloses the power unit and transmission, thereby protecting them not only from dust and dirt and the weather, but also against petty thievery of such things as: carburetor and magneto; further to provide a novel construction of transmission means; further to provide a novel construction of worm gear drive which allows for the same speed forward and reverse; further to provide a novel construction and means of mounting the worm gear and clutches; further to provide a novel construction of maximum simplicity, efficiency, economy, assembly and ease of operation; and such further objects, advantages and capabilities as will later more fully appear.

Our invention further resides in the combination, construction and arrangement of parts illustrated in the accompanying drawings, and while we have shown therein a preferred embodiment, we desire it to be understood that the same is susceptible of modification and change without departing from the spirit of our invention.

30. In the drawings:

Fig. 1 is a view in side elevation of our road roller.

Fig. 2 is a top plan view of the construction disclosed in Fig. 1.

35. Fig. 3 is a fragmentary view in side elevation of the internal combustion engine or prime mover for the road roller and the gear case housing the worm gears, and also including the means of lubricating the gears.

40. Fig. 4 is a view in vertical cross section taken on the line 4—4 of Fig. 5.

Fig. 5 is a view in vertical cross section taken on the line 5-5 of Fig. 6.

Fig. 6 is a fragmentary top plan view of the
45 construction disclosed in Fig. 7.

Fig. 7 is a fragmentary view in side elevation of the transmission and rear construction of the road roller, the side roller frame plate and one rear drive wheel having been removed.

50 Fig. 8 is a broken view in horizontal cross section taken on the line 8-8 of Fig. 7.

Referring more particularly to our invention, the numeral 1 refers to the prime mover or internal combustion engine for driving the road roller.

55 This roller is provided with front rolls 2 and rear

rolls 3 and 3^a of substantially greater diameter than the forward roll, the construction of the forward and rear rolls being such as to allow an overlap in the front rolls, such overlapping being especially advantageous when rolling over hot material.

Roller plates 4 and 5 provide a frame for the power plant and worm drive of the roller, this giving the same a stream-line appearance, and by enclosing the power unit and transmission completely, the plate protects the inner mechanism from dust and dirt and the weather, and also against petty thievery of the removable parts.

also against petty pilferage of the removable parts. Louvered plates 6 and 7 are provided in the frame or side plates. These louvered plates or doors are of ample size for inspection and when locked prevent ready removal or disturbance of the carburetor or electrical equipment. A re-

movable plate 8 also allows access to the clutches. The forward wheels or rolls 2 are provided with adjustable scrapers 9 and 10, while the rear rolls 3 and 3^a are provided with adjustable scrapers 11 and 12, this construction allowing for the scraping of the rolls, regardless of the direction of rotation of the rolls. 75

The steering mechanism for the road roller comprises a steering shaft 13 provided at one end with a hand wheel 14 for turning the same, and provided at the other end with a bevel gear 15 meshing with a larger bevel gear 16 mounted upon a shaft 17 provided with a worm (not shown) meshing with an arcuate rack 17^a mounted on the vertical shaft 18 connected to a yoke 19 containing the front or guiding rolls. The construction of the vertical shaft 18 or king pin 90 in combination with the yoke allows for the steering over rough surfaces as well as smooth, with the expenditure of but a small amount of energy by the operator.

In order to properly lubricate the drive and transmission means, we provide our construction with a spiral gear drive encased in a housing 20 (the gears not being disclosed), one of the gears being connected to the water pump shaft 21 which operates the water pump 22. The spiral gears drive the shaft 23 driving the gear pump 24 in the tank 25. This gear pump circulates oil in the worm gear casing 26, the oil being pumped thereto by means of a discharge line 27 connecting to the top of the gear casing, the oil draining back through an outlet 28 from the gear casing back to the tank 25. This construction thus provides a continuous circulation of oil through the worm gear casing. 95 100 105

A shaft 29 is driven directly from the prime 110.

mover or engine, and has mounted thereon a worm 30, the shaft being suitably and rigidly mounted upon bearings 31 and 32, the end of the shaft being threaded and provided with a nut 33 bearing against the beveled plate of the bearing 32. The bearing 31 is mounted within an annular flange 34, which member provides a portion of the side wall of the gear casing 26. The thrust roller bearing member 32 is mounted in a casing 35 attached to the rear wall of the housing 26. A hub 36 is splined on the shaft 29 and is provided with a series of flexible discs 37 bolted thereto, while a spider 39 is suitably bolted or attached to the fly wheel 40 and also suitably bolted or attached to the discs 37. This construction provides a flexible coupling allowing for any slight variation in alignment of the shaft. An upper worm gear 41 and a lower worm gear 42 mesh with and are always in engagement with the worm 30. The worm gears 41 and 42 are each provided with hubs 43 secured thereto by bolts 44, quills 45 being splined to said hub. Roller bearings 46 and 47 are mounted on the quills and between the hub 43 and end plates 48 and 49 of the gear casing 26. The upper and lower quills 45 are provided with an annular upstanding portion or plate 50 providing the rotating or driven part of the clutch. Attached to these plates are clutch plates 51 and 52 by means of bolts 53 or the like. Hubs 54 are keyed to the shafts 55. Sliding tooth connections or clutch members 56 and 57 are adapted to frictionally engage the clutch plates 51 and 52 respectively and be rotated thereby, the upper clutch members 56 and 57 and the member 58 on the hub 54, being connected to the hub and rotate the shaft 55 and drive the pinion 59 for driving the roller in reverse or rearwardly. When the lower shaft 55 is driven by means of the clutch mechanism, the pinion 60 is rotated and this pinion drives the roller in the forward direction. The upper and lower clutch and the driving mechanism therefor are similar in construction and have been numbered accordingly throughout the drawings.

In road roller operation, the most severe strains come on the clutches and it is therefore necessary that they be of ample size in order to stand up to the most severe work and strain day in and day out, year in and year out. Applicants' construction of clutches of the twin-disc type, in which the pressures are relatively low and frictional surfaces of ample size, provides clutches which are very long lived and require but infrequent adjustments, which adjustments may be made by hand without even the use of a wrench.

The construction for forcing the clutch into engagement or disengagement, comprises a clutch shift or shifter arm 61 which is pivoted at 62 upon a stub shaft which is mounted upon a plate 63, which plate is bolted to the side of the frame. The clutch shift or shifter arm 61 is provided at its upper and lower ends with yokes 64 and 65 which are attached to slidable sleeves 66 and 67. The yoke 64 is further attached to a second yoke 69 mounted on a stub shaft 70, the clutch shift being rocked by means of lever arms 71, 71^a, 72, 72^a and 73 provided with a forked connection 74 attached to the lever 75. Thus by either forcing the lever 75 forwardly or pulling it rearwardly, the upper clutch A or the lower clutch B may be thrown in to drive its respective pinion 59 or 60. The sleeves 66 and 67 are provided with wedge surfaces acting upon cam members 76 and 77 respectively, to force the movable clutch plates into engagement with those

connected to the quills 50, thus operating the clutch A or B to rotate either the upper or the lower shaft 55 and its respective pinion 59 or 60. The sleeves 66 and 67 are connected to the opposite ends of the shifter arm or clutch shift in such a manner that when one end of the clutch lever moves in to tighten its clutch, the other end moves away from clutching position, so that at no time can both clutches be in engagement. As shown in Fig. 5, the clutch is in neutral position. The ends of the shafts 55 adjacent the pinions 59 and 60 are provided with bearings 78 surrounded by an annular ring 79 providing a bushing therefor, the bearing and bushing being housed in a member 80, removably secured in a side wall of the frame of the roller. A fluidal metal such as zinc, is poured in at 81 between the bushings 79 and an annular shoulder 82 of the member 80. This allows for the proper alignment of the shaft 55.

As shown more clearly in Figs. 6 and 7, the pinions 59 and 60 drive a large pinion 83, this pinion 83 in turn driving a quill 84 upon which are mounted pinions 85, 86 and 87. A shaft 88 is located above and rearwardly of the shaft 84^a and is provided at one end thereof with a hub 89 upon which is mounted a bull pinion 90 adapted to mesh with a bull gear 91 fastened to the large roll 3^a and rear axle 92, by means of a differential. Pinions 93 and 94 are mounted on a slideable sleeve 95, which sleeve is adapted to be shifted by means of a shifter arm 96, thus bringing into engagement either the pinions 93 and 85, or the pinions 94 and 86. A pinion 97 on the shaft 88 is mounted on a slideable sleeve 98. A shifter arm 99 is adapted to slide the sleeve 98 and pinion 97 into or out of engagement with the pinion 87. Thus by the meshing or engagement of the pinions 85, 86 and 87 with their respective pinions 93, 94 or 97 on the shaft 88, it is possible to secure three speeds. In low speed, the pinion 87 meshes with the pinion 97; in second speed, the pinion 86 meshes with the pinion 94; while in high speed, the pinions 85 and 93 mesh. By the construction of the upper and lower clutches A and B and the pinions 59, 60 and 83, our construction allows for the same travelling speeds forward and reverse, the necessary feature in a road roller which is working backward substantially as much as forward. The shaft 84^a is stationary, the quill 84 being the rotating member.

In order to throw this machine into whichever speed is necessary, the shifter arms 96 and 99 are mounted upon upper and lower shiftable arms 100 and 100^a which are slidably mounted in bracket members 101 and 102. The arms 100 and 100^a are connected at their one end with members 103 and 104, the member 103 being connected to a gear shift lever 105, while the second or lower member 104 is connected to a gear shift lever 106. The upper lever 105 operating through the member 103 manipulates and shifts the upper shaft 100, which shaft or arm shifts either pinion 93 or 94 into high or second position. The lower lever 106 operating through the arm 104 operates the lower shaft or arm 100^a to throw the pinion 97 into or out of engagement with the pinion 87 so as to throw the machine into or out of low speed. Pins 107 and 108 pass through the shaft 84 at both sides thereof, these pins holding the mechanism on said shaft in rigid position and thus preventing any lateral displacement.

Whenever any one of the pinions 93, 94 or 97

is in engagement with its respective pinion on the shaft 84, the shaft 88 is rotated, thus rotating the bull pinion 90, which bull pinion rotates the bull gear 91 fastened to the rear roll and axle by means of a differential 109. The differential is provided with a side bevel gear 110 provided with a hub 111 keyed to the shaft and which provides the driving bevel gear. A spur drive gear 112 provided with four differential pinions 113, is free to revolve on the hub 111. The rear road wheel 3^a with its hub 114 and its connected bevel gear 115 is free to revolve on the rear axle unless the compensating action is locked, which can be accomplished by means of a pin 116, which pin 116 is generally inserted when the roller is pulling a heavy load. The bull pinion and the differential are completely enclosed in a dust-proof casing.

On the rear wheel 3 opposite the one carrying the differential, we provide a brake 117 which is provided with conventional brake band and operated through the means of a hand wheel 118. A pin 119 is adapted to lock the hub 120 to the brake drum 117.

From the drawings and the above detail construction, it will be seen that we have provided a construction of road roller which is very efficient and easily operated. By our construction of worm gear drive, in which we use the worm gears as the primary drive from the motor to the clutches, we have taken a most noteworthy step forward in the construction of road rollers. By using two worm gears, one located above and the other beneath the single worm, we have provided a construction which is exceedingly well adapted to the operation of a road roller, which, unlike a motor truck or other automotive vehicle, is working in reverse gear substantially as much as in forward gear, and must therefore have the same travelling speed forward and reverse. The construction of the worm gear drive requires practically no adjusting and permits an immediate reduction in speed from that of the motor to that of the clutch shaft.

By our construction of clutches, the worm gears, are fitted to quills or hollow shafts carried on tapered roller bearings, which are placed within the gear housing. These quills on which the worm gears are mounted carry the driven clutch discs while the hubs carry the remainder of the discs. The construction of the frame provides easy accessibility to the interior mechanism, while at the same time, it prevents the entrance of any foreign matter and the weather. Although the drawings disclose but a single hand or emergency brake, the construction is provided with a foot brake operated by means of a drum bolted to the pinion or the lower clutch shaft. All of the levers are easily accessible to the operator of the machine, and the entire construction lends itself to simplicity of operation.

Having thus disclosed our invention, we claim:

1. In a road machine, a power plant for said machine, a worm connected to the drive shaft of said machine, a worm gear located below said worm for driving said machine in forward direction, and a second worm gear located above said worm for driving said machine in reverse direction, said gears being mounted on quills, clutch discs attached to said quills, a shaft freely rotatable within each of said quills, clutch discs connected to said shafts and adapted to be engaged and rotated by the clutch discs attached to said quills, and a gear mounted on each of said last mentioned shafts and rotated thereby

for operatively driving said machine in either of two directions.

2. In a road machine, a power plant for said machine, a worm connected to the drive shaft of said machine, a worm gear located below said worm for driving said machine in forward direction, and a second worm gear located above said worm for driving said machine in reverse direction, said gears being mounted on quills, clutch discs attached to said quills, a shaft freely rotatable within each of said quills, clutch discs connected to said shafts and adapted to be engaged and rotated by the clutch discs attached to said quills, means for engaging either of said clutches for driving its respective shaft, and a gear mounted on each of said last mentioned shafts and rotated thereby for operatively driving said machine in either of two directions.

3. In a road machine, a power plant therefor, driving wheels for said machine, and means for transmitting the motive power from the drive shaft of said power plant to said wheels, said means including a worm connected to and directly driven from the drive shaft, worm gears located above and below said worm and driven thereby 100 and mounted upon quills, a shaft freely rotatable in each of said quills, a clutch adapted to connect each of said quills with its respective shaft, a pinion mounted on each of said shafts, and driving means connecting said pinions with said 105 driving wheels for operating said machine.

4. In a road machine, a power plant for said machine, a worm connected to the drive shaft of said machine, worm gears positioned above and below said worm and driven thereby, each gear 110 being mounted upon a quill, clutch discs on said quills, a shaft within each of said quills and freely rotatable therein and provided with a hub at one end and a pinion at the other end thereof, clutch discs mounted on said hubs and 115 adapted to be engaged and driven by the clutch discs on said quills, said pinions meshing with a common driven gear mounted upon a quill, pinions mounted on said quill, a shaft, pinions on said shaft, each of said second mentioned pinions being adapted to be engaged by and rotate a pinion on said shaft, a bull pinion on said shaft and a gear adapted to be engaged by said bull pinion and driven thereby for propelling 120 said machine.

5. In a road machine, a power plant therefor, driving wheels for said machine, and means for transmitting the motive power from the drive shaft of said power plant to said wheels, said means including a worm connected to and directly driven from the drive shaft, worm gears mounted on quills and driven by said worm, a shaft freely rotatable in each of said quills, a clutch adapted to connect each of said quills with its respective shaft, and means for throwing into or out of engagement either of said 130 clutches.

6. A drive mechanism for a road machine, comprising a worm and gears, a pair of clutches, driven members for driving said machine in either forward or reverse direction, each of said clutches having elements connected to a gear and to a driven member, pinions on said members, a gear meshing with and adapted to be driven by either of said pinions, and means driven 140 by said last mentioned gear for selectively driving said machine.

FRANK S. DAVIS.
